UNITED STATES PATENT OFFICE.

FREDERICK W. KING, OF CLEVELAND, OHIO.

DESIGN FOR A GOGGLE-CASE.

49,217.

Specification for Design. Patented June 20, 1916.

Application filed February 25, 1916. Serial No. 80,531. Term of patent 14 years.

To all whom it may concern:

Be it known that I, FREDERICK W. KING, a citizen of the United States, residing at Cleveland, in the county of Cuyahoga and State of Ohio, have invented and produced a certain new, original, and ornamental Design for a Goggle-Case, of which the following is a specification, reference being had to the accompanying drawings, forming part thereof.

In the drawings, Figure 1 is a plan view

of a goggle case showing my new design. Fig. 2 is a side elevation, and Fig. 3 is an end elevation thereof.

I claim:

The ornamental design for a goggle case, as shown.

FREDERICK W. KING.

Witnesses:

E. L. THURSTON,
E. B. GILCHRIST.
